UNITED STATES PATENT OFFICE.

GEORGE W. PIERCE, OF CAMBRIDGE, MASSACHUSETTS.

APPARATUS FOR RECEIVING OR RELAYING ELECTRIC SIGNALS.

1,112,655.

Specification of Letters Patent.

Patented Oct. 6, 1914.

Application filed August 5, 1913. Serial No. 783,088.

To all whom it may concern:

Be it known that I, GEORGE W. PIERCE, a citizen of the United States, residing at Cambridge, in the county of Middlesex and 5 State of Massachusetts, have invented certain new and useful Improvements in Apparatus for Receiving or Relaying Electric Signals; and I do hereby declare the following to be a full, clear, and exact description 10 of the invention, such as will enable others skilled in the art to which it appertains to make and use the same.

The present invention relates to apparatus for receiving or relaying electric signals, and 15 more particularly to apparatus in which a gaseous conductor or conductors are utilized for amplifying the received or relayed impulses or signals.

The object of the invention is to produce 20 an efficient and comparatively simple apparatus by means of which feeble received electric impulses may be detected and amplified into comparatively much greater impulses in an electric circuit which is directly or indirectly connected with a translating or signal 25 indicating device.

With the above object in view the present invention consists of apparatus for receiving or relaying electric signals hereinafter described and more particularly pointed out in 30 the claims.

In the drawings, which illustrate the preferred embodiment of the present invention, Figure 1 is a diagrammatic view of the apparatus used in connection with wireless telegraphy or telephony; Fig. 2 is a modification illustrating another form of the apparatus for use in connection with wireless telegraphy or telephony; Figs. 3 and 4 are diagrams illustrating two modifications of the apparatus for use with wire signaling; Fig. 35 5 is a diagram showing three vapor or gaseous devices connected together; Fig. 6 is a diagram showing the multiplicity of terminals inclosed in the same vessel; and Fig. 45 7 is a modification showing a mercury arc as the ionizing means at the cathode.

Referring to the illustrated embodiment 50 of the invention, and more particularly to Fig. 1 of the drawings, the antenna 1 is connected through the primary 2 of an oscillation transformer 3 to the ground 4. The signal impulses or current waves set up in the antenna cause corresponding oscillations 55 in the closed secondary circuit 5 which includes a secondary 4 of the transformer and

a condenser 6. This circuit 5, taken in conjunction with the antenna, may be for convenience designated as the receiving circuit. The receiving circuit is connected to the amplifying device through leads R_1 and R_2 , which may be designated as receptor leads or connections because it is through them that the received impulses or oscillations are led to the amplifying device. A condenser C is 60 interposed in one of the receptor leads. In the construction shown in Fig. 1 the condenser is interposed in the receptor lead R_2 .

The amplifying device illustrated in Fig. 1 consists of two vapor or gaseous devices 70 indicated generally by M_1 and M_2 , which are interconnected so as to cause the received signal impulses impressed on the gaseous device M_1 to set up corresponding impulses in an electric circuit connecting M_1 to M_2 . 75 The impulses of this connecting circuit, in turn, through the action of the gaseous device M_2 , set up impulses in another circuit which is connected to the translating or signal indicating device. The gaseous device M_1 consists of an evacuated vessel V_1 , of glass or quartz, preferably glass, in which are inclosed a cathode K_1 , an anode A_1 and a screen S_1 . The screen S_1 is preferably a grid consisting of a piece of iron or platinum wire bent back and forth to form a number of separated and parallel grid bars or elements. The screen may be made of a piece of open-work woven metallic fabric having interstices between the wires thereof. 85 The cathode K_1 continuously emits negative ions and for this purpose it is made of a filament, preferably of tungsten, which is heated to incandescence. A battery 10 connected to the cathode filament through an 90 adjustable rheostat 11 furnishes the current for heating the filament. The cathode filament K_1 , its leading-in wires 12 and 13, the rheostat 11 and battery 10, constitute a local heating circuit. The receptor lead R_2 is connected to the leading-in wire 12 of this local 95 heating circuit. The anode A_1 is a plate, preferably of nickel or iron. The anode and cathode are placed in proximity to each other and between them is interposed the 100 screen.

The second gaseous device M_2 consists of an evacuated vessel V_2 inclosing a cathode K_2 , an anode A_2 and screen S_2 , which are substantially identical in construction with 110 the cathode, anode and screen in the first vessel V_1 . The cathode filament K_2 is

heated by the current in a local heating circuit which comprises leading-in wires 21 and 22, an adjustable rheostat 23 and a battery 24. The screen S_2 is connected by 5 means of a wire 30 to the anode A_1 . The leading-in wires 13 and 21 of the cathodes K_1 and K_2 respectively are connected by a wire connection 31 in which is included a battery B_1 , the negative pole of which is 10 connected to the cathode K_1 . The closed circuit from the cathode K_1 , across the evacuated space to the anode A_1 , along the wire 30 to the screen S_2 , across the evacuated space from the screen S_2 to the adjacent cathode 15 K_2 or anode A_2 or both, and along their leading-in wires to the wire 31 and through the battery B_1 back to the cathode K_1 , constitutes a local battery circuit designated for convenience by the reference letter L. The 20 anode A_2 is connected through a lead wire D_1 to a signal indicating device T. The cathode K_2 is connected through its leading-in wires, a battery B_2 and lead wire D_2 to the signal indicating device T. The negative pole of 25 the battery B_2 is connected to the cathode K_2 . The closed circuit from the cathode K_2 , across the evacuated space to the anode A_2 , along the wire D_1 through the signal detecting device T, along the wire D_2 through 30 the battery B_2 and through the lead wires back to the cathode K_2 constitutes a closed local circuit which, for convenience, may be designated as the indicator circuit D. The 35 leads D_1 and D_2 since they connect the amplifying device with the signal indicating device T may be termed the responder or indicator leads or connections.

While the operation of the apparatus is not perfectly understood, nevertheless for 40 the sake of completeness and explicitness in the disclosure of the invention, the probable operation will be described and explained in accordance with the prevailing electronic theory of electricity. The rheostats 11 and 45 23 are adjusted until the two cathode filaments K_1 and K_2 are heated to incandescence, in which condition they continuously emit negative ions or electrons. The battery B_1 tends to set up a current in the local 50 connecting circuit L in such a direction as to cause a current of negative electricity to pass across the ionized evacuated space from the cathode K_1 to the anode A_1 . The incandescent cathode filament K_1 ionizes the space 55 between it and the anode A_1 and allows the negative current to pass between them. The result is that the screen S_2 which is connected through the wire 30 and the vessel V_1 to the negative pole of the battery B_1 is 60 maintained at a potential negative with respect to the cathode K_2 which is connected to the positive pole of the same battery B_1 . The negative charge given to the screen S_2 leaks away across the evacuated space in the 65 vessel V_2 , but is normally replenished by

conduction through the evacuated vessel V_1 . The battery B_2 causes a negative current to tend to flow from the incandescent cathode filament K_2 across the evacuated ionized space to the anode A_2 . If the screen S_2 is disconnected from the battery B_1 , it allows the negative ions to pass through its interstices from the cathode K_2 to the anode A_2 . If, however, the screen S_2 is connected to the battery B_1 , as shown in the drawings, 70 the screen S_2 by virtue of its negative charge greatly reduces the flow of ions from the cathode K_2 to the anode A_2 and thus reduces the current in the indicator circuit D. It is obvious that, if the negative charge or potential of the screen S_2 fluctuates, corresponding current fluctuations will be caused in the indicator circuit D. Since the negative charge on S_2 is continuously leaking off 80 across the evacuated ionized space in the vessel V_2 and is being continuously replenished by the negative current flowing across the ionized space from the cathode K_1 to the anode A_1 , it is obvious that fluctuations in the negative current flowing from the cathode K_1 to the anode A_1 will cause fluctuations 85 in the charge on the screen S_2 , which in turn will cause fluctuations in the current in the indicator circuit D. The fluctuations in the negative current flowing across the ionized space from the cathode K_1 to the anode A_1 is caused by fluctuations in the potential of the screen S_1 . The screen S_1 gets a negative charge from the negative ions 90 shot out from the cathode K_1 which strike the screen. This negative charge which the screen normally possesses, is not, however, sufficient to prevent the flow of the negative current across the gap from the cathode K_1 to the anode A_1 , although it undoubtedly 100 has some effect in preventing the free passage of the negative ions across this space. If the potential of the screen S_1 is varied it is obvious that the more negative the potential of the screen S_1 with respect to the cathode K_1 , the greater the action of the screen S_1 in preventing or damming the flow of the current across from the cathode K_1 to the anode A_1 .

The potential of the screen S_1 with respect to the cathode K_1 is varied by the oscillations set up in the receiving circuit R_1 . The variations in potential at the poles of the condenser 6 are transmitted over the receptor leads R_1 and R_2 and cause corresponding 110 momentary variations in the relative potential of the screen S_1 and cathode K_1 . These fluctuations in the potential of the screen S_1 cause corresponding fluctuations in the negative current flowing over the wire 30 to the screen S_2 , and consequently cause variations 115 in the potential or negative charge of the screen S_2 . The induced variations in the potential of the screen S_2 with respect to the cathode K_2 cause corresponding variations in the 120

current which flows across the gap from the cathode K_2 to the anode A_2 . These current variations are transformed into audible or visible signals by means of the signal indicating device T . The comparative feeble current waves in the receiving circuit 5 set up larger current waves or variations in the local connecting circuit L and these waves or variations in turn set up still larger current waves or variations in the indicator circuit D so that much more energy is available for operating the signal indicating device T than is received by the receiving circuit. With these effects there is combined a rectifying action at the screens.

In practice, the voltage of the batteries B_1 and B_2 depends upon the degree of exhaustion in the vessels V_1 and V_2 and also upon the distance between the cathodes and anodes and screens in said vessel and also probably upon the size of the mesh of the screens. The cathode, anode and screen are preferably as close together as practicable, for example, from two to eight millimeters apart. While the voltages of the batteries B_1 and B_2 have to be adjusted, it has been found that the battery B_1 may be in the neighborhood of about five volts, while the battery B_2 is in the neighborhood of about fifty volts. The battery B_2 should be of sufficient voltage to cause a considerable current to flow through the detector circuit D when the screen S_2 is disconnected from the lead wire 30, and the battery B_1 should be of sufficient voltage to normally maintain the screen S_2 at a potential sufficiently negative with respect to the cathode K_2 to very materially cut down the current in the detector circuit D . While the vessels V_1 and V_2 may be exhausted to about the same degree, nevertheless it is preferable to maintain the vessel V_2 at a higher degree of exhaustion than the vessel V_1 . In practice it is found convenient to introduce a small quantity of mercury into the vessel V_1 and then to exhaust the vessel by a Gaede molecular pump by means of which the exhaustion is carried out until the absolute pressure within the vessel V_1 is the vapor pressure of the mercury in contact with the liquid mercury. On pumping the vessel it is preferred to heat the filament and to apply heat to the vessel during the last stages of pumping to expel residual gas. With the vessel V_1 thus exhausted, the vessel V_2 is exhausted with a Gaede molecular pump, the exhaustion being preferably carried out until the absolute pressure within the vessel V_2 is less than the vapor pressure in the vessel V_1 . The exhaustion in the vessel V_2 is determined by a trial as follows. The degree of exhaustion of the vessel V_2 is varied and the magnitude of the response in the indicator circuit D to received signals of standard intensity is noted and the degree of exhaustion is determined experimentally to give the maximum response.

In Fig. 2 a modified apparatus for receiving and amplifying wireless messages is shown. The apparatus illustrated in Fig. 2 differs from that illustrated in Fig. 1 in that a common battery 110 is used to heat the cathode filaments K_1 and K_2 . In this modification of the apparatus the battery B_1 which maintains the screen S_2 at a negative potential is included in the connection 30 between the screen S_2 and the anode A_1 . The two wires 116 and 117 which form the heating circuit for the two cathode filaments act in parallel to form part of the local circuit L of the battery B_1 . The form of apparatus illustrated in Fig. 2 has the advantage over that illustrated in Fig. 1 of employing but a single battery to heat the cathode filaments. By means of the rheostats 118 and 119 the heating currents of the two filaments can be adjusted independently.

In Fig. 3 is diagrammatically illustrated a modification of the apparatus which is particularly adapted for use in connection with signaling over wires. The current impulses or signals come in over the line wires 301 and through the primary 302 of the transformer 303. One end only of the transformer secondary 304 is connected to the amplifying device by means of a single receptor lead R_1 between the transformer secondary and the screen S_1 . The transformer sets up variations of potential in the screen S_1 through the unilateral connection R_1 . The unilateral connection is effective probably on account of the minute capacity of the wires which act as a substitute for a wire connection through a condenser of very small capacity from the unconnected end of the secondary 304 to the cathode K_1 . In this connection it may be remarked that in the apparatus illustrated in Fig. 1 the condenser C may have a very small capacity, or may be entirely omitted under some conditions. It is found in practice that under some conditions, and particularly with wire signaling, that the use of a unilateral connection from the receiving circuit to the screen S_1 gives sharper signals at the signal indicating device than is the case when there is also a connection to the cathode K_1 .

In Fig. 4 another modification of the apparatus is illustrated. The signaling impulses to be detected come in over line wires 401 and through the primary 402 of the transformer 403. Both of the terminals of the transformer secondary 404 are connected to the amplifying device through the receptor leads R_1 and R_2 . In this figure the condenser C is illustrated as interposed in the receptor lead R_1 . So far as the successful operation of the apparatus is concerned, it is apparently immaterial whether the condenser C is interposed in the receptor lead R_1 .

- or the receptor lead R_2 . The signal detecting device in the indicator circuit D is illustrated in Fig. 4 as comprising both a local indicating apparatus T_1 and a relaying device T_2 . The local indicating apparatus T_1 , 5 may be an electromagnetic relay, or the like, or a telephone connected either directly in the detector circuit D or indirectly connected, as, for example, through a transformer. The relaying device T_2 may be a transformer in the case of telephony or a relay in the case of telegraphy. The relaying device T_2 relays the signals on to a line wire T_3 by means of which the amplified signals may be transmitted to a distant station. The local indicating device T_1 and the relaying device T_2 , 10 may be connected in series, as illustrated, or in parallel, or one of them may be omitted. The translating or signal indicating device indicated generally by T in the other figures, 15 and described in the claims as a signal indicating device, is intended to include both local translating or indicating devices such as any telephone or relay directly or indirectly connected with the indicator circuit D and relaying devices such as a transformer by means of which the amplified impulses are sent to a distant station where they are detected. 20 In Fig. 4 there is illustrated the preferred pressure regulating device for the evacuated vessel V_1 . An extension 440 of the vessel V_1 contains liquid mercury 441. Around the extension is a coil 442 of resistance wire which may be heated by electric current furnished by the battery 443. This heating current can be varied by means of the adjustable rheostat 444, or may be replaced by a cooling bath. The vessel V_1 is exhausted as 25 completely as possible, and thereafter the desired degree of pressure in it is had by varying the temperature of the mercury 441 to vary its vapor pressure in the vessel V_1 . By this means the pressure in the vessel may be varied until the maximum response in the local circuit L is secured. 30 In Fig. 5 there are illustrated the connections for three vapor or gaseous devices M_1 , M_2 and M_3 . The cathode filaments K_1 , K_2 and K_3 are heated by a common battery 510. The gaseous device M_1 is connected with the secondary circuit 505 of a wireless receiving apparatus by a bilateral connection formed by the receptor leads R_1 and R_2 , similar to 35 the bilateral connections shown in Figs. 1 and 2, the only difference being that the condenser C is illustrated as interposed in the receptor lead R_1 . The gaseous device M_1 is connected with the gaseous device M_2 by a local battery circuit L_1 similar to the connection shown in Fig. 2, by means of which the screen S_2 is given momentary fluctuations in potential. The anode A_2 is connected through a section of the local battery circuit 40 L_2 to a third gaseous device M_3 . The varia-

tions in potential of the screen S_2 causes corresponding but greater variations in the screen S_3 . The variations in potential of the screen S_3 cause variations in the current in the indicator circuit D which are read by the signal indicating device T . The apparatus illustrated in Fig. 5 may be considered as essentially the same as that illustrated in Figs. 1 and 2 with the interposition of a third gaseous device between the second gaseous device and signal indicating device. It is obvious that, as shown in Fig. 5, a third gaseous device, or perhaps more gaseous devices, may be connected between the second gaseous device and the signal indicating device. Therefore, when in the claims the circuit connecting the second cathode and second anode is described as being connected to a signal indicating device, it is to be understood that this is intended to include constructions like that shown in Fig. 5 in which the connection from this circuit to the signal indicating device is had through another gaseous device or equivalent interposed apparatus. 45

In Fig. 6 the two gaseous devices M_1 and M_2 , of which in the other figures each comprise a separate evacuated vessel, have their electrodes inclosed in a single evacuated vessel V . In place of two separate cathodes a common cathode K is employed. On one side of the common cathode K is the anode A_1 and its screen S_1 which is connected to the receiving circuit. On the other side of the common cathode K is the anode A_2 with its screen S_2 . The cathode K is an incandescent filament heated by the current from the battery 610. The anode A_1 and screen S_1 are connected in local circuit L which includes the battery B_1 , by means of which the screen S_2 is maintained at a negative potential. The anode A_2 is connected through the battery B_2 to the signal indicating device T . The form of apparatus illustrated in Fig. 6 has the advantage in that but a single evacuated vessel need be used, and the further advantage that the cathodes K_1 and K_2 are consolidated into a single cathode filament K . This form of apparatus has the disadvantage that it is impossible to independently 110 adjust the pressure of the gaseous conducting space around the two sets of anodes and screens A_1 and S_1 , and A_2 and S_2 respectively. 115

In Fig. 7 is illustrated a modification of the devices for ionizing the conducting space in the neighborhood of the cathode. The evacuated vessel contains the cathode K_1 , anode A_1 , and screen S_1 . The anode A_1 is at the top of the vessel with the screen S_1 beneath it. The cathode K_1 instead of being an incandescent filament, is formed by a circular plate 770 through which is a hole 771, and which is supported over a body of liquid mercury 772 in the bottom 120

of the vessel. In the mercury 772 is an iron or platinum electrode 773 which is connected to a battery 710. The battery 710 furnishes the current to maintain a mercury arc between the plate 770 and the mercury 772. This mercury arc is the ionizing means for the cathode. The screen S_1 is connected with the receiving circuit through a receptor circuit R_1 . The cathode K_1 is connected to the receiving circuit by a second receptor lead R_2 . The anode A_1 is connected by means of a connecting wire 730 to a second gaseous device, and the cathode K_1 is connected through a wire 731 to the second gaseous device, these external connections of the vessel being substantially the same as those indicated in the other figures of the drawing. The cathode may either be in itself the source of ionization, as, for example, an incandescent filament, or the cathode may have separate provision or means for ionizing the space surrounding the cathode; as, for example, the mercury arc illustrated in Fig. 7.

The present invention in its broader aspects is not limited to a cathode which in itself is the source of ionization, the essential thing being that the cathode has provision either in itself or separate from it whereby the space surrounding the cathode is ionized and rendered conducting.

The apparatus of the present invention is applicable for the reception or relaying or recording of an amplification of electric signals of radio telegraphy, of radio telephony, and telegraphy and telephony over land lines and cables and over submarine cables.

The apparatus makes use of gaseous conductors as parts of its conducting circuits. By "gaseous conductor" is meant the region or portion of the conducting system where the ordinary metallic conductors are intercepted one from another except for the interposition of a space rendered partly conductive or convective for electricity by some ionizing agency such as, for example, the incandescent filaments or the mercury arc illustrated in the drawings, or some equivalent ion-producing agent such as an electrode maintained at a high potential, a radio-active substance, a Wehnelt cathode, a photoelectric terminal, or similar ionizing device. Although the evacuated space within the vessels is spoken of as a gaseous conductor, it is to be understood that for some purposes everything within one or more of the vessels that can be removed by a vacuum pump is removed. Under these conditions, an electric current across the evacuated space is, according to the prevalent electric theory, carried by the electrons emitted from one or the other of the terminals. In addition to the conductive or convective action of the electrons from

the terminals, a part of the conduction or convection of current may be effected in some cases by electrons supplied by a residuum of gas or vapor left within the vessel. The term "gaseous conductor" is intended to define the space or region between the terminals across which electricity is carried by conduction or convection by means of ions or electrons whether the space is exhausted to the last degree possible and the current passes by the ions or electrons emitted from the terminals, or the conducting ions or electrons are supplied from a gas in the space itself.

While it is preferred to make the screens in the form of wire grids as above described, and to have these grids of about the same area as the anode plates and interposed between the anode plates and the cathode, nevertheless the construction of the screen is not limited to the preferred embodiment. It is believed that a satisfactory arrangement may be had by making the screen of a piece of openwork wire fabric or of a perforated plate bent into a hollow cylinder and surrounding the cathode, the anode being a similar and larger cylinder surrounding the screen. The term "screen" is not intended necessarily to limit the construction of the screen to the form of a grid or wire fabric, but the term "screen" is intended to define any conducting body which, by virtue of its shape, its position with relation to the anode and cathode, and its electric charge, operates to more or less prevent the free passage of the current-carrying ions between the cathode and anode.

As shown in the drawings, it is preferred to put a condenser in one of the receptor leads, in order that the negative charge imparted to the screen S_1 may not have a free conducting path to the cathode K_1 . The value of the capacity of the condenser is best determined by experiment. This capacity, in practice, is comparatively small. In fact, in the construction illustrated in Fig. 3, it may be considered that the capacity in the receptor lead between the transformer secondary and cathode K_1 is reduced to zero.

The circuit to which the receptor leads are connected to conduct the received impulses to the amplifying device is spoken of as the receiving circuit. This circuit may be the circuit in which the oscillations are set up in a wireless receiving station or may be the circuit with which the impulses are transmitted in wire signaling. The receptor leads may be connected directly to the circuit or may be connected through a transformer, such as is shown, for example, in Figs. 3 and 4, where the receptor leads are connected to the transformer secondary and are thus coupled with the line wire circuit.

While the preferred embodiment of the

present invention has been specifically illustrated and described, it is to be understood that the present invention is not limited to its illustrated embodiment but may be embodied in other constructions of electric signaling apparatus within the scope of the invention as particularly pointed out in the following claims.

I claim—

- 10 1. Apparatus for receiving or relaying electric signals, having, in combination, an evacuated vessel, a cathode having provision for emitting negative ions, and an anode and its screen inclosed in said vessel, a second evacuated vessel, a second cathode having provision for emitting negative ions, and a second anode and its screen inclosed in said second vessel, means for conducting signal impulses to the first screen to vary its potential, a local circuit including a source of electromotive force and a conductive electrical connection between the first anode and second screen, and a second circuit having a connection with a signal indicating device and including a source of electromotive force and a connection between the second cathode and second anode.
- 15 2. Apparatus for receiving or relaying electric signals, having, in combination, at least one cathode having provision for emitting negative ions, an anode, a screen in proximity to the anode, a second anode, a second screen in proximity to the second anode, said elements being surrounded by gaseous conducting space, means for conducting the electric signal impulses to the first screen to vary its potential, a local circuit including a source of electromotive force and a conductive electrical connection between the first anode and second screen, and a second circuit connected with a signal indicating device and including a source of electromotive force and a connection between the second anode and a cathode.
- 20 3. Apparatus for receiving or relaying electric signals, having, in combination, at least one cathode, a plurality of anodes and screens therefor, said elements being surrounded by gaseous conducting space, a receptor connection to one screen, a conductive electrical connection between another screen and an anode, and a connection from another anode and a cathode to a signal indicating device.
- 25 4. Apparatus for receiving or relaying electric signals, having, in combination, an evacuated vessel, a cathode, anode and screen inclosed therein, a second evacuated vessel and a second cathode, anode and screen inclosed therein a receptor connection to the first screen, a conductive electrical connection between the second screen and first anode, and a connection from the second anode and second cathode to a signal indicating device.
- 30 5. Apparatus for receiving or relaying electric signals, having, in combination, at least one cathode having provision for emitting negative ions, an anode, a screen in proximity to the anode, a second anode, a second screen in proximity to the second anode, said elements being surrounded by gaseous conducting space, means for varying the potential of the first screen in response to the received signal impulses, means including a conductive electrical connection from the first anode to the second screen and an external unidirectional source of electro-motive force in the connection for maintaining a difference of potential between the second screen and first anode and having provision for causing variations in the potential of the second screen corresponding to variations in the potential of the first screen, and means having a connection with a signal indicating device for causing an electric current to flow between the second anode and a cathode.
- 35 6. Apparatus for receiving or relaying electric signals, having, in combination, an evacuated vessel, a cathode having provision for emitting negative ions and an anode and its screen inclosed in said vessel, a second evacuated vessel, a second cathode having provision for emitting negative ions and a second anode and its screen inclosed in said second vessel, means for varying the potential of the first screen in response to the received signal impulses, means including an external unidirectional source of electro-motive force for maintaining the second screen at a different potential from the second cathode and having provision for causing variations in the potential of the second screen corresponding to variations in the potential in the first screen, and means having a connection with a signal indicating device for causing an electric current to flow between the second anode and the second cathode.
- 40 7. Apparatus for receiving or relaying electric signals, having, in combination at least one cathode having provision for emitting negative ions, an anode and its screen, a second anode and its screen, said elements being surrounded by gaseous conducting space, a connection to the first screen for causing variations in its potential corresponding to the received signal impulses, a local circuit including a connection between the first anode and second screen and a source of electromotive force for maintaining a difference of potential between the second screen and first anode, and a connection between the second anode and a cathode including a source of electromotive force.
- 45 8. Apparatus for receiving or relaying electric signals, having, in combination, an evacuated vessel, a cathode having provision for emitting negative ions and an anode.

- anode and its screen inclosed therein, a second evacuated vessel, and a second cathode having provision for emitting negative ions and an anode and its screen inclosed therein, a connection to the first screen for causing variations in its potential corresponding to the received signal impulses, a local circuit including a connection between the first anode and second screen and a source of electromotive force for maintaining a second screen at a potential negative with respect to the second cathode, and a connection between the second anode and second cathode including a source of electro-motive force. 5
- 16 9. Apparatus for receiving or relaying electric signals, having, in combination, at least one cathode having provision for emitting negative ions, a plurality of anodes and their screens, a receiving connection to one screen, a conductive electrical connection between another screen and the anode which is adjacent the first screen, and a connection from another anode and a cathode to a signal indicating device. 10
- 25 10. Apparatus for receiving or relaying electric signals, having, in combination, an evacuated vessel, a cathode having provision for emitting negative ions, and an anode and its screen in proximity to the cathode inclosed within said vessel, means for maintaining the screen at a negative potential with respect to the cathode by a current supplied through a similar evacuated vessel and for superimposing on said negative potential variations in potential corresponding to the signal impulses, and means including a connection to a signal indicating device for causing an electric current to flow between the cathode and anode. 30
- 35 11. Apparatus for receiving or relaying electric signals, having, in combination, an evacuated vessel, a cathode having provision for emitting negative ions and an anode and its screen adjacent the cathode inclosed within said vessel, means tending to cause a current to flow between the anode and the cathode, means including a source of electromotive force and a partly gaseous path for normally maintaining the screen at a potential negative with respect to the cathode, and means for causing variations in the potential of the screen corresponding to the signal impulses. 40
- 45 12. Apparatus for receiving or relaying electric signals, having, in combination, an evacuated vessel, a cathode having provision for emitting negative ions and an anode and its screen inclosed in said vessel, a second evacuated vessel, a second cathode having provision for emitting negative ions and a second anode and its screen inclosed in the second vessel, means for causing variations in the potential of the first screen corresponding to the signal impulses, a circuit across the evacuated space from the first cathode to the first anode, along a wire connection to the second screen, across the evacuated space from the second screen to an adjacent electrode and back along a wire connection to the first cathode, such circuit including a source of electromotive force tending to cause a negative current to flow from the first cathode to the first anode, and a second circuit across the evacuated space from the second cathode to the second anode, said circuit including a connection to a signal indicating device and a source of electromotive force for causing a negative current to flow from the second cathode to the second anode. 50
- 55 13. Apparatus for receiving or relaying electric signals, having, in combination, an evacuated vessel, a cathode having provision for emitting negative ions and an anode and its screen inclosed therein, means for causing variations in the potential of the screen corresponding to the signal impulses, and means tending to cause a current to flow across the evacuated vessel between the cathode and anode, and a body of liquid mercury inclosed in the evacuated vessel for maintaining a vacuum at the desired degree of exhaustion. 60
- 65 14. Apparatus for receiving or relaying electric signals, having, in combination, an evacuated vessel, a cathode having provision for emitting negative ions and an anode and its screen inclosed therein, means for causing variations in the potential of the screen corresponding to the signal impulses, and means tending to cause a current to flow across the evacuated vessel between the cathode and anode, a body of liquid mercury inclosed in the evacuated vessel, and means for independently adjusting the temperature of the mercury to adjust the vapor pressure of the mercury within said vessel. 70
- 75 15. Apparatus for receiving or relaying electric signals, having, in combination, a local circuit including a source of electromotive force, an amplifier including a plurality of electrodes surrounded by a gaseous conductor and connected with the local circuit and operating to produce impulses in the local circuit corresponding to but of greater intensity than the received signal impulses, a second circuit including a source of electromotive force and a connection with a signal detecting device, and a second amplifier including a plurality of electrodes surrounded by a gaseous conductor, said second amplifier being conductively electrically connected with both circuits and operating to amplify the current impulses in the first circuit to produce impulses in the second circuit corresponding to but of greater intensity than the impulses in the first local circuit. 80
- 85 16. Apparatus for receiving or relaying electric signals, having, in combination, a 120

local circuit including a source of electro-motive force, an amplifier including a cathode, anode and screen surrounded by a gaseous conductor, said amplifier having a connection from its anode and cathode to the local circuit and a connection for leading the received impulses to its screen and operating to produce impulses in the local circuit corresponding to but of greater intensity than the received signal impulses, a second circuit including a source of electro-motive force and a connection to a signal detecting device, and a second amplifier including a cathode, anode and its screen surrounded by a gaseous conductor and having its cathode and anode connected to the second local circuit and its screen conductively electrically connected to the first local circuit and operating to amplify the impulses in the first local circuit to produce impulses in the second local circuit corresponding to but of greater intensity than in the first local circuit.

17. Apparatus for receiving or relaying electric signals, having, in combination, two evacuated vessels each inclosing a cathode and anode and its screen, a connection for leading the signal impulses to the screen in the first vessel, a circuit including a source of electromotive force connecting the two vessels and including the cathode and anode in the first vessel and the screen and one of the electrodes in the second vessel, and a second circuit connected to the anode and cathode in the second vessel, and including a source of electromotive force and a connection to an electric signal device, said second vessel being maintained at a greater degree of exhaustion than the first vessel.

18. The combination, with the line wire, of apparatus for receiving or relaying electric signals transmitted over wires, comprising an evacuated vessel, a cathode, anode and its screen inclosed therein, and a unilateral connection between the apparatus and the line wire.

19. The combination, with the line wire, of apparatus for receiving or relaying electric signals transmitted over wires, comprising a cathode having provision for emitting negative ions, an anode and its screen in proximity to the cathode, said elements being surrounded by a gaseous conductor, a connection between the cathode and anode including a source of electro-motive force, and a unilateral connection between the apparatus and the line wire

consisting of a receptor lead connected to the screen.

20. The combination, with the line wire, of apparatus for receiving or relaying electric signals transmitted over wires, comprising an evacuated vessel, a cathode, anode and screen inclosed therein, a connection between the cathode and anode including a source of electromotive force, a transformer having its primary in series with the line wire and a unilateral connection between the transformer and the apparatus consisting of a receptor connection from one terminal of the transformer secondary to the screen, the other terminal of the secondary being unconnected with the apparatus.

21. Apparatus for receiving or relaying electric signals, having, in combination, an anode, a screen in proximity to the anode, a second anode, a second screen in proximity to the second anode, means for ionizing the space about said elements, means for conducting electric signal impulses to the first screen to vary its potential, a local circuit including a source of electro-motive force and a conductive electrical connection between the first anode and second screen, and a second circuit connected with a signal indicating device and including a source of electro-motive force, and a connection between the second anode and the ionizing means.

22. Apparatus for receiving or relaying electric signals, having, in combination, a cathode and an anode and screen in proximity to the cathode, a second cathode and a second anode and second screen in proximity to the second cathode, all the said elements being surrounded by evacuated ionized space, means for conducting electric signal impulses to the first screen to vary its potential, a local circuit including a source of electro-motive force and a conductive electrical connection between the first anode and second screen for maintaining a difference in potential between them, and a second circuit having a connection with a signal indicating device and including a source of electro-motive force and a connection between the second cathode and second anode.

GEORGE W. PIERCE.

Witnesses:

ALICE ACKRAYD,
BURTON W. CARY.

It is hereby certified that in Letters Patent No. 1,112,655, granted October 6, 1914, upon the application of George W. Pierce, of Cambridge, Massachusetts, for an improvement in "Apparatus for Receiving or Relaying Electric Signals," an error appears in the printed specification requiring correction as follows: Page 2, lines 62 and 71, for the reference-letter "B" read " B_1 "; and that the said Letters Patent should be read with this correction therein that the same may conform to the record of the case in the Patent Office.

Signed and sealed this 10th day of November, A. D., 1914.

[SEAL.]

R. F. WHITEHEAD,

Acting Commissioner of Patents.
